UNITED STATES PATENT OFFICE.

RICHARD LICHTENSTERN, OF VIENNA, AUSTRIA.

METHOD FOR IMPREGNATION OF UNPAVED STREETS.

No Drawing. Application filed July 21, 1925, Serial No. 45,121, and in Austria August 7, 1924.

Already various remedies have been proposed for preventing or indeed for diminishing the formation of dust on roads without as yet one of these dust-binding remedies 5 having had a full result. The lack of efficiency of the dust-binding remedies is to be explained thereby, that the oil—for the most part any kind at all of oily residual product of the distillation of petroleum, an- 10 thracite or lignite is employed—after a little time soaks under the road covering, whereby the road surface dries and the old condition of the road is again produced.

There is therefore the question as to pro- 15 viding a permanent insoluble and impene- trable layer that prevents the soaking in of the oil, if the formation of dust is to be stopped efficiently and not merely in a transitory way.

20 According to the invention this is effected by utilizing the lime always richly present in the material of which the road is made, for producing insoluble lime soap. By this mode of procedure in a simple way the road 25 is successfully provided with an impervious covering layer. If now any oily dust-bind- ing medium is applied it remains permanent- 30 ly efficient, and the question of the dusting off is therewith to be considered as solved.

35 The production of the lime soap can re- sult from the decomposition of sodium or potassium soaps with the calcium present in the road dust as oxide or carbonate. The naphthene soaps that form refuse in the refining of petroleum have shown themselves especially suitable for this purpose. The application of the dust-binding medium is 40 effected in that a mixture of sodium or potassium soap with any oil usual for this purpose is incorporated in the road surface for example by rolling, whereby the desired formation of calcium soap is effected in the earth itself.

45 It is very suitable to add to the said mix- ture material that at higher temperature is soft or fluid, for example heavy residual oil containing paraffin. Therewith during the hot day time a road surface is formed wet with oil, whereby the binding of newly 50 formed dust is secured.

The proportion in the mixture of the sev- eral constituents depends naturally on the condition of the road. For a normal road, for example, that has been in existence 55 already for a long time and is made of hard

broken stone with finer sand, a product of the following composition is necessary:—

About 1 to 1½ parts of naphthene soap are dissolved in 30 to 40 parts of residue containing paraffin with application of moderate heat, or emulsified and 60 to 70 parts of a normal oil distillate, added according to the necessary consistency. The finished material is spread in cold or warm condition on the road surface as finely and uniformly 65 as possible and by means of brooms or other apparatus rubbed into the road covering. The road is then directly usable again, the dust has disappeared.

The more lime the road material con- 70 tains, the more soap may be employed. The more soap employed, the less must be em- ployed the residue, containing paraffin, be- cause the impervious layer, merely treated with distillate, does not need more moisture, 75 but operates exactly as an ideal road cover- ing, like an asphalt covering.

It is of course possible, indeed, to employ a product that consists from 20 to 40 and more 80 parts of naphthene soap or other soap solu- tion or of soap and of up to 100 parts of lighter or heavier distillates (mixed oils).

The choice of appropriate material in in- dividual cases must be left to the operators.

In the new construction of roads the mate- 85 rial is applied appropriately either with or without the addition of water, at the rolling in of the broken stone—sand layer and then after the rolling of the uppermost layer also this once more is impregnated with the prod- 90 uct of the like or suitably altered constitu- tion.

What I claim is:—

1. Process for impregnating unpaved roads which comprises forming in the road 95 a layer insoluble in water and impervious to oil and applying above it an oily dust- binding medium.

2. In a process for impregnating unpaved roads, forming a layer impervious to oil, 100 the said layer being formed from the lime present in the material of which the road is formed.

3. In a process for impregnating unpaved roads, forming a layer impervious to oil by 105 reaction of a soap of naphthene acid containing an alkali metal with a compound of calcium containing oxygen in the material of which the road is formed.

4. In a process for impregnating unpaved 110

roads as claimed in claim 3 the reaction of a soap of naphthene acid containing sodium with a compound of calcium containing oxygen in the material of which the road is formed.

5. In a process for impregnating unpaved roads as claimed in claim 3 the reaction of a soap of naphthene acid containing potassium with a compound of calcium containing 10 oxygen in the material of which the road is formed.

6. In a process for impregnating unpaved roads as claimed in claim 3 the reaction of a soap of naphthene acid containing sodium 15 with the calcium carbonate in the material of which the road is formed.

7. In a process for impregnating unpaved roads as claimed in claim 3 the reaction of a soap of naphthene acid containing potassium, with the calcium carbonate in the material 20 of which the road is formed.

8. In a process for impregnating unpaved roads adding the residue from the refining of petroleum rich in paraffin to a mixture of 25 naphthene soap with an oil.

9. In a process for impregnating unpaved roads as claimed in claim 3 incorporating a mixture of the soap with an oil in the road surface by rolling.

30 10. In a process for impregnating unpaved roads, dissolving between 1 and 1½ parts

of naphthene soap in between 30 and 40 parts of petroleum distillation residue containing paraffin with application of heat and between 60 to 70 parts of a normal oil distillate, and diffusing the prepared material 35 on a road.

11. An earth road containing a layer of a water insoluble soap and an oily material.

12. An unpaved road having a layer containing a soap impervious to oil and a layer superposed thereupon containing an oily material.

13. An unpaved road having a surface containing an oily material and a calcium 45 soap.

14. An earth road having a layer containing a soap capable of resisting the penetration of oily material within the earth through said layer.

50 15. An earth road having a layer containing a water insoluble soap capable of resisting the penetration of oily material within the earth through said layer.

16. An earth road having a layer containing a calcium soap resistant to the penetration of oil.

55 17. An earth road having a layer containing a calcium compound of naphthene soap.

In testimony whereof I affix my signature.

RICHARD LICHTENSTERN.
